UNITED STATES PATENT OFFICE.

JAMES LE ROY COSBY, OF ALBUQUERQUE, NEW MEXICO.

RAILWAY TRACK.

1,415,802.

Specification of Letters Patent.

Patented May 9, 1922.

Application filed February 4, 1922. Serial No. 534,115.

To all whom it may concern:

Be it known that I, JAMES L. COSBY, a citizen of the United States, and a resident or Albuquerque, in the county of Bernalillo 5 and State of New Mexico, have invented certain new and useful Improvements in Railway Tracks, of which the following is a specification.

This invention relates in general to a 10 railway track, and more particularly to an improved railway tie for use in railway tracks.

The object of the invention is to provide an improved railway tie constructed entirely 15 of metal and which may be conveniently constructed of a single piece of metal and which is so organized with the rail as to obviate the necessity of bolts, spikes, screws, wedges, or similar fastening devices, and 20 yet at the same time positively support and engage the rails in such manner as to absolutely preclude any possibility of the rails spreading or creeping.

Another object is to provide a tie of this 25 character which while being of light weight construction, is at the same time susceptible of being firmly or strongly ballasted or anchored.

A further object is to provide a metallic 30 tie of this character which possesses within certain limits a capacity for flexion, the tie being such that after a limited degree of flexion has been partaken of to relieve the tie structure of destructive stresses, the parts 35 will come into bracing and positive engagement in such a manner as to constitute a beam or supporting element of great strength and rigidity.

Another object is to provide a tie of this 40 character wherein provision is made for draining so as to reduce the liability of the tie corroding or deteriorating.

Other objects and advantages of the invention reside in certain novel features of 45 construction, combination and arrangement of parts which will be hereinafter more fully described and particularly pointed out in the appended claims, reference being had to the accompanying drawings forming part of 50 this specification, and in which:

Figure 1 is a perspective view, illustrating a portion of a railway track embodying the tie constituting the present invention;

Figure 2 is a plan view, illustrating one 55 mode in which the tie constituting the present invention may be constructed;

Figure 3 is a fragmentary plan view of the complete tie, the rail being removed;

Figure 4 is a view in transverse vertical section on line 4—4 of Figure 3; and

Figure 5 is a similar view on line 5—5 of Figure 3.

Referring to the drawings wherein for the sake of illustration is shown the preferred embodiment of the invention, the numeral 60 10 designates generally the ties which when organized in a track are arranged as usual in spaced parallel relation and extend transversely and beneath the rails, designated at 11.

The ties which constitute the present invention are preferably constructed entirely of metal and have generally the form of a channel in cross section, each tie accordingly comprising a base 12 and upright 65 70 side flanges 13 and 14.

In manufacturing the tie it may be constructed from blanks, as indicated in Figure 2, and when so constructed the resilient metal which composes it is preferably bent 80 on longitudinal lines *a* and *b* to provide side flanges 13 and 14. The side flanges 13 and 14 include enlarged portions, designated at 13^a and 14^a, the enlarged portions being provided at the center of the tie and extending 85 outwardly from the blank and upwardly in the complete tie. Between the enlarged portions 13^a and 14^a of the flanges and the contiguous portions of the base section 12

slots, designated at 15 and 16, are cut or 90 otherwise formed, and these slots define a reduced and flexible portion, designated at 12^a, in the base 12. When the tie is formed, the portions 13^a and 14^a of the side flanges are bent inwardly, as shown in Figures 1, 3 and 5 and the portion 12^a of the base is bent upwardly, as shown in Figures 1 and 5, so that the lower edges of the inwardly curved portions 13^a and 14^a lie immediately above and slightly spaced from 95 the upwardly curved portion 12^a of the base. The portions 12^a, 13^a and 14^a are possessed of a capacity of limited flexion and after they have been flexed to their limit they come into positive and bracing engagement 100 with each other, in such manner that the tie constitutes a beam of great rigidity and strength.

Adjacent the ends of the tie a pair of lugs, 110 designated at 17, are provided, the members of each pair being alined and being formed on the flanges 13 and 14. These lugs are

bent inwardly to provide supports for tie plates 20 upon which the rails 11 are seated. As shown in Figure 2, the lugs 17 are formed partly from the metal which makes up the flanges 13 and 14 so that when these lugs are bent inwardly, as shown in Figure 4 they form notches in the flanges and the flanges adjacent these notches present shoulders or abutments, designated at 18, which prevent lateral displacement of the tie plates 20 and which also engage the bases of the rails 11 to prevent spreading of the rails, as shown to advantage in Fig. 1. The tie plates 20 have intermediate their ends lips 21 preferably formed integral with the tie plate, the lips being struck from the resilient metal which constitutes the tie plate. In the railway track the lips 21 are arranged in notches 11^a formed in the base of the rails 11 and the ends of the lips are bent, as at 21^a to overlie the base of the rails and to engage the top surfaces of the same. In this manner the lips 21 constitute clamps for preventing vertical displacement of the rails and also prevent creeping of the rails or longitudinal movement thereof, this latter action being by virtue of its disposition in the notches formed in the base of the rails. The shoulders or abutments 18 formed on the flanges 13 and 14 serve to prevent spreading or lateral movement of the rails, and thus the forces which tend to spread the rails do not act upon the lips 21 but are taken up by these shoulders 18.

When the ends of a tie are subjected to downward pressure, as for instance when a train passes over the track, the base section 12 is subjected to compression and the flanges 13 and 14 are under tension. These forces however do not tend to distort the tie, as under the action of compression the upwardly curved portion 12^a of the base section flexes upwardly and under tension the inwardly curved portions 13^a and 14^a of the flanges flex outwardly. If the pressures to which the tie is subjected are of a very high degree the flexion of these curved portions 12^a, 13^a and 14^a continues until the lower edges of the portions 13^a and 14^a come into engagement with the top of the curved portion 12^a. This engagement of these portions exerts a bracing action as between these curved portions and by virtue of this engagement the tie constitutes a beam of great rigidity and strength when such properties are necessary, the tie at the same time having such resiliency or capacity for flexion as to enable it to take up all ordinary stresses or strains without danger of distortion and without injury to the elements which comprise the tie.

It is obvious that the tie may if desired be entirely constructed of a single piece of metal. If the tie is constructed of a single piece of metal the lugs 17 are omitted and the tie plates 20 are integrally formed with

one of the flanges as for instance the flange 13 and are then bent over until their free ends rest upon the flange 14, the flanges 13 and 14 being notched at the tie plates to provide the shoulders 18 for engaging the rail as in the construction illustrated. It is understood of course that in both forms of the invention the tie plates are welded or suitably secured to the flanges.

I claim:

1. A railway tie constructed entirely of metal and comprising a channel including a base section and side flanges, the side flanges having enlarged portions adjacent the center of the tie, the tie having slots formed between said enlarged portions of the side flanges and the contiguous portion of the base, the slots forming a reduced portion in the base and the reduced portion being curved upwardly, the enlarged portions of the side flanges being curved inwardly so as to lie immediately above and slightly spaced from said upwardly curved portion of the base, the tie having adjacent its ends means adapted to support and engage the rails whereby when the tie is subjected to pressure the upwardly curved portion of the base will flex upwardly and the inwardly curved portions of the side flanges will flex outwardly, the inwardly curved portions being adapted to come into positive and bracing engagement with the upwardly curved portion when the pressures to which the tie is subjected are of a high degree.

2. A railway tie constructed entirely of metal and comprising a channel having a base section and side flanges, the base section and the side flanges having flexing portions adapted to come into bracing and positive engagement after having partaken of a certain degree of flexion, said side flanges having means for engaging and supporting rails.

3. A railway tie constructed entirely of metal and comprising a channel having a base section and side flanges, the base section and the side flanges having flexing portions adapted to come into bracing and positive engagement after having partaken of a certain degree of flexion.

4. A railway tie comprising a channel including a base section and side flanges, the base section and side flanges having flexion portions adjacent the center of the tie adapted to come into positive and bracing engagement after having partaken of a certain degree of flexion, the side flanges adjacent the ends of the tie being notched to provide shoulders adapted to engage the rails to prevent spreading, tie plates supported upon the side flanges and extending between the notched portions thereof and rail engaging means carried by said tie plates.

5. In combination with the rail having notches in its base, a tie comprising a chan-

nel including a base section and side flanges, the side flanges having notches therein defining shoulders engageable with the base of the rail for preventing spreading movement thereof, a tie plate carried by the side flanges and extending between the notches of said side flanges and lips struck from the tie plate and adapted to be extended through the notches of the bases of the rail and to be engaged with the top surfaces of the bases of the rail to prevent creeping and vertical displacement of said rails.

6. A railway tie constructed of resilient metal and comprising a channel including a base section and side flanges, the side flanges having enlarged portions adjacent the center of the tie, the railway tie having slots between the side portions of the flanges and the contiguous portion of the base section, the slots defining a reduced portion in said base section, the reduced portion of

said base section being upwardly curved and the enlarged portions of the side flanges being inwardly curved so as to lie above 25 and slightly spaced from the upwardly curved portion of the base section.

7. In combination with a rail, a railway tie constructed of resilient metal and comprising a channel including a base section 30 and side flanges, the base section and side flanges being provided with flexing portions adjacent the center of the tie adapted to come into positive and bracing engagement after having partaken of a certain degree 35 of flexion, said side flanges being provided with notches adjacent the ends thereof, the notches presenting shoulders adjacent the rails for preventing spreading thereof, tie plates extending between the side flanges 40 and extending between the notched portions thereof and rail engaging means carried by said side flanges.

JAMES LE ROY COSBY.
